UNITED STATES PATENT OFFICE.

ALFRED E. WALLER, OF BRONXVILLE, NEW YORK, ASSIGNOR TO WARD LEONARD ELECTRIC COMPANY, A CORPORATION OF NEW YORK.

RHEOSTAT.

Application filed May 7, 1924. Serial No. 711,564.

This invention relates particularly to rheostats in which the resistive conductors are connected to a series of contact buttons, over which a movable contact arm passes for cutting resistance in and out of circuit as desired. The invention not only comprises an improvement in rheostats but also in the method of making rheostats.

One object of the invention is to provide an improved method and form of construction which will be economical in cost of material and labor and which may be rapidly and conveniently manufactured. Another object is to provide a construction which will permit the contact buttons to occupy a minimum amount of space. Another object is to provide a form of contact buttons which may be rapidly made automatically in one operation from stock material. Another object is to provide a construction and method of assembly of the contact buttons with the resistive conductors which will insure the making of good electrical connection between the conductors and the contact buttons. Another object is to provide a simple form of construction which is well adapted for receiving and electrically connecting resistive conductors of different sizes and for the connection of the terminal wires to the end buttons, while insuring good electrical contact of the parts. Other objects and advantages of the invention will be understood from the following description and accompanying drawings which illustrate a preferred embodiment thereof.

Fig. 1 is a plan view, partly broken away, of a rheostat embodying the invention; Fig. 2 is an enlarged cross-section showing a portion of the rheostat plate and one of the contact buttons and embedding insulation; Fig. 3 is a side view of one form of contact button in its initial state; Fig. 4 is a similar view of another form of contact button in its initial state; Fig. 5 is a plan view of another form of contact button; Fig. 6 is a side view thereof in its initial state; Fig. 7 is a plan view showing the method of initial assembly of the contact buttons and resistive conductors; Fig. 8 is a cross-section indicating the method of compressing the contact buttons and Fig. 9 is a similar view showing the method of compressing part only of a compound contact button.

Referring to Figs. 1 and 2, a form of rheostat is shown having the well known

metal plate or disk 1 provided with an upturned edge 2. The edge 2 is provided with projecting ears which carry the terminals 3. The metal plate is provided with a ground coat 4 of insulating material, and an insulating adhesive enamel coating 5 embeds the resistive conductors 6 and the lower portion of the contact buttons 7, as well as a conducting terminal ring 8. A pivoted contact arm 8' carries a conductor bridging the ring 8 and contact buttons 7, so that when the contact arm is moved, it will successively cut in or cut out from circuit varying amounts of resistance, as is well understood.

Fig. 3, shows a cylindrical form of contact having the body portion 9, a neck 10 and a lower ring 11, the lower face of the ring 11 having a central depression 12. Fig. 4 shows a similar contact with an additional neck 10' and an additional ring 11', the outer surface of the latter having the central depression 12.

Considering first the form shown in Fig. 3, the resistive conductor is united therewith by taking the resistive conductor, which has been previously formed of zig-zag shape, and bending it at the desired point around the neck 10 of the contact button; and then, at the next desired point of contact of the resistive conductor, placing a portion thereof around the neck of the next contact button and so on. This may be conveniently done by use of a template 13 as shown in Fig. 7. The contact buttons are placed in holes in the template 13 of a proper size and properly placed for the particular requirement, the lower ends of the contact buttons being uppermost. The resistive conductor is then bent around the neck of the first contact button, a proper length of conductor then laid out on the plate and bent at its outer end and then led to and passed around the neck of the next contact button and so on until the requisite amount of resistive conductor and number of contact buttons are provided for the particular rheostat desired. In some cases the resistive conductor may be bent around the neck of each contact button before the same is placed in its hole in the template and in some cases one or more complete turns of the conductor may be made around the neck of the contact. The template is then placed under a plunger as indicated in Fig. 8 and the plunger is forced downwardly on the face of the ring 11. This compresses the

ring 11 and neck 10 so as to firmly clamp the conductor in place which secures a good and permanent electrical connection to the contact button. The contact buttons are previously annealed so that when compressed, a practically solid block or contact button is produced. The depression 12 in the end of the ring 11 tends to avoid the conductor being forced out of the slot and also permits the ring to be more easily and intimately forced into close engagement with the conductor. It also permits a slight spreading of the ring 11 without great exertion of force giving a somewhat larger base portion to the contact button than the remaining part thereof, as indicated in Fig. 2. This slight spreading of the base permits the enamel coating 5 to more firmly hold the contact button in position. If the depression 12 is not provided, more force will be necessarily given to the plunger 14 in order to secure an intimate engagement of the conductor with the contact button and to secure a sufficient compression and flattening of the parts. The plunger 14 is shown as adapted to be operated manually by a pivoted arm 15, but obviously the same may be automatically operated in regular sequence at intervals of time sufficient to permit the operator to place the next contact under the plunger after the previous one has been compressed. Also a spring release of the plunger may be arranged, whether operated manually or automatically, so as to insure the same amount of force being exerted in compressing each contact button. After compressing the contact buttons as described, they are placed upon the ground coat 4 of the rheostat plate in proper relation to each other and with the conductors properly placed on the ground coat. The parts are then covered with the material for forming the enamel and baked in a furnace in the usual manner. The face of the contact buttons are then ground to lie in the same plane for insuring an even and good electrical connection with the contact arm.

In some cases conductors of different sizes are connected to the same contact button, or the ends of two conductors of the same size connected. In such cases, especially where the conductors are different in size, or comparatively large, it is found that a better contact can be secured and the connection more easily made, by providing an additional neck 10' and an additional ring 11' as shown in Fig. 4. In such a case the end of one conductor will be wound around one neck and the end of the other conductor wound around the other neck. One compression operation will then serve to give the required union of the parts. The body portion 9 is made a little shorter in this case than when a single neck and single ring is used, so that when compressed, the total depth of the contact buttons will be approxi-

mately the same where both forms of contact buttons are used in the same rheostat. Also the terminal wires 16 are usually of copper and of larger size than the resistive conductor; and in such a case the form of contact buttons shown in Fig. 4 is also advantageous, one of the necks receiving the resistive conductor and the other receiving the terminal conductor. The terminal conductor is usually added to the end button, or buttons, before the resistive conductor has been united with the contact buttons by compression; and in such a case when compressing the contact button which is later to receive the resistive conductor, a split washer 17 is inserted around the neck which is later to receive the resistive conductor, as shown in Fig. 9. This contact button can then be compressed to hold the terminal conductor in place without compressing the parts which are to later receive the resistive conductor. The split washer 17 is afterwards removed and the resistive conductor placed around the remaining neck; and the contact button is again compressed to also hold the resistive conductor in place. Where convenient, the operation of compressing the contact button having the two conductors thereon, may, of course, be done in one operation instead of successively.

In some form of rheostats it is desirable to use a form of contact having an elongated surface as shown in Figs. 5 and 6. Here the body 9' is shown elongated, as likewise the parts 11^a and 11^b, corresponding to the rings 11, 11' of the cylindrical form of contact. The necks 10^a and 10^b correspond with the necks 10, 10', of the cylindrical contact, and the lower face of the elongated form of contact will preferably have formed therein the central depression 12'. The method of assembling and compressing the parts is of course the same with elongated form of contact as with the circular form already described.

The contact buttons are obviously of a form which permits them to be made rapidly and economically from cylindrical rods for the form shown in Figs. 3 and 4 and from flattened rods for the form shown in Figs. 5 and 6. The buttons are conveniently made in a machine of the screw machine type and all of the parts formed, including cutting off the buttons, in one operation.

This improvement is not only economical in permitting low cost of material and labor but is particularly advantageous in the reduced size of the contact buttons and space occupied by them on the rheostat plate, the necessity of extensions from the face of the buttons for connection to the resistive conductor and terminal leads being avoided. The simple method of uniting the conductor with the contact buttons by compression is

also accomplished quickly and conveniently, while at the same time insuring a good electrical connection.

In some cases the neck of the contact buttons may be made eccentric with reference to the axis of the contact button, and this may be desirable in facilitating the bending and uniting of the conductor with the contact buttons.

10. Although a preferred embodiment of this invention has been shown and described, it is evident that various modifications may be made therein as may be desirable to fulfill particular requirements for various sizes and types of rheostats.

I claim:

1. A rheostat comprising resistive conductors, contact buttons having outwardly extending body portions and having outer contact surfaces, and an insulating coating for embedding the inner portions of said buttons, said contact buttons having reduced neck portions receiving said conductors and having inner end portions compressed against said conductors.

2. A rheostat comprising resistive conductors, contact buttons, and an insulating coating for embedding the inner portions of said buttons, said contact buttons having a main portion having outer contact surfaces, a reduced portion and a portion compressed against said main portion and against the conductor.

3. A rheostat comprising resistive conductors, contact buttons, and an insulating coating for embedding the inner portions of said buttons, said contact buttons having a main portion having outer contact surfaces, a neck portion near one end thereof and an inner end portion compressed against said main portion and conductor.

4. A rheostat comprising resistive conductors, contact buttons, and an insulating coating for embedding the inner portions of said buttons, at least one of said contact buttons comprising a main portion having outer contact surfaces, a plurality of reduced portions, and a plurality of portions adjoining the reduced portions and compressed against the conductors and main portion.

5. The method of making a rheostat which comprises forming the contact buttons from a solid piece of material with a reduced

neck portion and inner ring portion, looping the resistive conductors around said reduced portions, compressing the inner ring portions against the conductors, and embedding said conductors and compressed portions of said contact buttons in insulating material.

6. The method of making a rheostat which comprises forming the contact buttons with reduced necks near the ends thereof and with inner enlarged portions adjoining said necks, looping the resistive conductors around said neck portions, compressing said inner portions against said conductors to enlarge said outer portions, and embedding said conductors and compressed portions of said contact buttons in insulating material.

7. The method of making a rheostat which comprises forming the contact buttons with a reduced neck portion and an enlarged portion adjoining said neck, and forming a depression in the outer surface of said enlarged portion, looping the resistive conductor around said reduced portion, compressing said enlarged portion against the conductor, and embedding the conductor and compressed portion in insulating material.

8. The method of making a rheostat which comprises forming a contact button with reduced neck portions and with enlarged portions adjoining said reduced portions, forming a depression in the outer surface of one of said enlarged portions, looping conductors around said reduced portions, compressing said enlarged portions against said conductors, and embedding said conductors and compressed portions of said contact button in insulating material.

9. The method of making a rheostat which comprises forming the contact buttons with a main portion, a reduced neck portion and an inner enlarged portion adjoining the neck portion, placing said contact buttons in a template and looping the resistive conductor around said reduced portions, compressing said enlarged portions against said conductor and main portions while positioned in said template, removing said contact buttons and conductor from said template and placing them upon an insulating support, and embedding said conductor and compressed portions of said contact buttons in insulating material.
